UNITED STATES PATENT OFFICE.

GEORGE R. McALLASTER, OF ROCHESTER, NEW YORK.

BED.

1,383,648.

Specification of Letters Patent.

Patented July 5, 1921.

Application filed April 5, 1918. Serial No. 226,949.

To all whom it may concern:

Be it known that I, GEORGE R. McALLASTER, a citizen of the United States, and resident of Rochester, in the county of Monroe and State of New York, have invented certain new and useful Improvements in Beds, of which the following is a specification.

The present invention relates to beds and more particularly to the type in which the bed frame is mounted to swing upon a suitable support to an upright position in order that, when not in use, it may be arranged more compactly in a room, an object of this invention being to provide means for securing the bed clothes so that they will be automatically shifted away from the mattress when the bed frame is thrown upright and will be automatically assembled on the mattress when the bed frame is thrown down. Another object of the invention is to permit the ends of the bed clothes at the swinging end of the bed to be tucked under the bed frame when the bed is lowered. Still another object of the invention is to provide separate and relatively movable rods to which the individual bed clothes are secured, said rods being movable on guides at the swinging end of the bed frame to carry the clothes in spaced relation to each other and to the mattress.

To these and other ends the invention consists of certain parts and combinations of parts, all of which will be hereinafter described, the novel features being pointed out in the appended claims.

In the drawings:—

Figure 1 is a side view of the bed in an upright position showing the panels or screen members open;

Fig. 2 is a section on the line 2—2, Fig. 1;

Fig. 3 is a sectional view through the bed showing the latter in position for use;

Fig. 4 is a fragmentary view of one side of the bed;

Fig. 5 is a side view of the bed in an upright position with the panels removed;

Fig. 6 is a fragmentary view of the upper end of the bed while the latter is upright, the screen being removed;

Fig. 7 is a detail view of the front end of the bed in operative position with the panels removed;

Fig. 8 is a detail view of the supporting means for the foot of the bed;

Fig. 9 is an enlarged detail section of the frame showing one of the handles of the sliding frame;

Fig. 10 is a detail view showing the manner in which the handles interlock with the bed frame;

Figs. 11 and 12 are enlarged detail views of one of the rods to which the bed clothes are secured;

Figs. 13 and 14 are detail views showing another form of the rods;

Figs. 15 and 16 are detailed views of still another embodiment of the invention, in which the rods are permanently held in spaced relation and are mounted to swing upon a sliding frame;

Fig. 17 is a detailed view of a further embodiment of the invention, in which the rods are relatively movable and are mounted to swing upon a sliding frame;

Fig. 18 is a view of an embodiment in which permanently spaced rods are mounted to swing upon a sliding frame the form of the mounting of the rods being different from that shown in Figs. 15 and 16; and

Fig. 19 is a still further embodiment of the invention, in which permanently spaced rods are mounted to slide upon a sliding frame.

In the illustrated embodiment of the invention there is provided a support comprising a base portion 1 and two uprights 2 made of any suitable material. To the upper ends of the uprights 2 the bed frame 5 is pivoted as at 3 at a point in spaced relation to the head of the bed. Preferably, the pivots 3 are arranged on lateral projections 4 at the upper ends of the uprights so that the frame will be inclined slightly when it is thrown to an upright position with its head end resting against the uprights below the pivots, thus preventing the bed frame from accidentally swinging downwardly.

The bed frame 5 in this instance is rectangular in form and has a spring mattress 100 supporting frame 6 connecting its transverse members. At the free or swinging end of the bed frame, a second supporting means is provided. This supporting means forms one of the features of this invention and comprises, in this instance, two extensible legs

connected together by a cross piece 7. Each leg may comprise an inner member 8 pivoted at 9 to a vertical flange of a side bar of the bed frame, and a tubular outer member 10 receiving the inner member telescopically. The outer member rests at one end on the floor and has its inner end adapted to abut the horizontal flange of a side bar of the bed frame, a slot 11 being provided so that the pivoted portion 9 may extend therethrough. The cross piece 7 connects the outer members 10. To each outer member a brace 12 is also pivoted at 13, said brace being further pivoted at 14 to the bed frame. With this arrangement, when the bed frame is swung to an upright position, the weight of the outer members of the legs, together with the swinging brace 12, causes the outer members to slide outwardly on the inner members, thus permitting the braces and the leg members to fold automatically in parallel relation, as shown in Figs. 5 and 6. The lowering of the bed frame automatically produces the reverse action, so that the supporting means for the foot of the bed requires no attention.

Another feature of this invention is the manner of securing the mattress to the bed frame so that it will be comfortable to the user, and yet will be held firmly to the bed frame. This means, in this instance, comprises a rope or cable 16 which is passed about the sides and head end of the mattress 15 and through eyes 17 on the foot piece of the bed frame and is then tied to the foot piece. At the head end of the mattress a board or strip 15^a is arranged to prevent the rope or cable distorting the mattress. By this arrangement the mattress is entirely free of the bed frame except at the swinging end, and the cable is so located that it does not interfere with the free use of the mattress or the tucking of the bed clothes under the mattress.

Still another feature of this invention is the means by which the bed clothes are held in spaced relation to each other and the mattress to provide for their airing when the bed is folded in upright position. This means is independent of the legs so that it may be adjusted while the bed is lowered.

In the embodiment shown in Figs. 1 to 12, this means comprises a frame consisting of two arms 18 guided in blocks 19 secured to the top faces of opposite side bars of the bed frame, so that the frame as a whole is adjustable longitudinally of the bed frame. At the outer end of each arm there is a portion 20 bent downwardly, a portion 21 bent inwardly, a portion 22 bent downwardly, a portion 23 bent outwardly, and a portion 24 bent upwardly and slightly inwardly. The portions 24 of the two arms are connected by a horizontal portion not shown. The inner ends of the arms (see Figs. 9 and

10) are bent laterally at 26 and are provided with rollers 27 operating on the upper face of the bed frame, and beyond the rollers the arms are bent downwardly at 28 and formed into handles. The adjacent inner edges of the bed frame may be formed with notches 29 in which the handles engage in order that the longitudinally movable frame may be held projected from the bed frame, as shown in Fig. 5.

The portions 23 and 24 act as guides for relatively movable rods 30 which extend from one side of the bed frame to the other. In this instance, these rods project beyond opposite sides of the bed and are formed at opposite ends with eyes 31 which operate on the guide portions 23 and 24. The eyes 31 are readily opened by unhooking the free ends from the body of the rod, and in this way a sheet may be quickly changed. Blocks 32 may be arranged on the rods to hold them spaced from each other. Each rod may also carry a number of clamps 33 of any suitable construction adapted to engage one of the bed clothes. In this instance, 90 each rod carries three of said clamps 33, one at the center of the rod, and one at each end of the rod beyond the guided portions. The bed clothes are indicated at *a*, *b* and *c*.

Assuming the bed is in its lowered position, as shown in Fig. 7, the rods will lie on the portions 23 of the frame beneath the forward end of the bed frame. Before swinging the bed upwardly the rods are moved off of the portions 23 to the lower parts of the portions 24, after which the bed frame is swung to its upright position, as shown in Fig. 5. This will permit the rods 30 to slide toward the free ends of the guides 24 and assume the position shown in Fig. 5, except that the lower ends of the bed clothes will rest upon the floor, due to the fact that the frame at the foot of the bed is in its innermost position. To raise the bed clothes off the floor the handles 28^a are moved upwardly simultaneously until they enter the notches 29, which will lock the longitudinally-movable frame in this projected position shown in Fig. 5. With the lowering of the bed frame the rods will fall downwardly on the guiding portions 24, after which the sliding frame is moved inwardly. The portions 23 extend under the bed frame in spaced relation to the latter, and permit the rods to move under the bed frame so that the bed clothes are tucked under such bed frame at the foot of the bed. The supporting legs are spaced from the end of the bed frame so that this movement of the rods is permitted.

Owing to the fact that the clothes are supported by clamps 33 beyond the sides of the bed frame by means of extensions on the rods beyond the guides, the edges of the bed clothes will fall over the sides to the mattress without wrinkles. At the foot of the 130

bed the bed clothes may be tucked under the bed frame by moving the rods rearwardly on the portions 23. It will thus be seen that the raising of the bed frame automatically 5 separates the bed clothes, to provide air spaces between them, while the lowering of the bed frame automatically deposits the bed clothes on the mattress in position for use.

In Figs. 13-14 an embodiment is shown 10 in which the rods 30^a are provided with coils 31^a at each end, which coils act to space the rods from each other, thus dispensing with the spacing blocks 32 of the embodiment shown in Figs. 11 and 12.

In the embodiment shown in Figs. 15 and 16, rods 30^b are held in a fixed spaced relation by arms 24^b, which are pivoted at 34 to two slides 35 guided at 36 on the sides of the bed frame. The slides 35 are deflected outwardly at 37, so that the bars 30^b will be of greater length than the width of the bed frame, thus permitting the bed clothes to be held beyond the sides of the bed frame in order that they may fall naturally over the 20 sides of the mattress. Stop members 38 are provided on the slides 35 in order to limit the swinging movement of the arms 24^b in one direction. In using this construction the bed frame is swung upwardly and, at the 25 same time, the bars 30^b and the arms 24^b are elevated so that the bars will support the bed clothes in spaced relation when the bed frame is upright. The sliding frame formed by the slides 35 and the parts carried there- 30 by is, after the bed frame is elevated, projected from the foot of the bed so that the bed clothes will not drag on the floor at their lower ends. With the lowering of the bed frame, the rods 30^b fall automatically to their lowermost positions and then the frame 35 is shifted inwardly to the dotted line position. If desired, the rods 30^c may be relatively movable, as shown in Fig. 17, in which case their ends may be projected from

40 the sides of the swinging arms 24^c which are pivoted directly to the slides 35 as at 34^c. In Fig. 18 the rods 30^d are rigidly connected to two L-shaped members 24^d pivoted at 34^d to slides 36^d, the operation being substantially the same as that shown in Figs. 15 and 16. In Fig. 19 the rods 30^e are rigidly connected to two slides 24^e which operate in guide sleeves 34^e carried at the free ends of slides 36^e, said slides having downwardly-deflected portions 36^e so that the rods 30^e may be dropped, as shown in dotted lines, to a plane below the plane of the mattress when the bed frame is in position for use. When the bed frame is upright, the 50 rods will lie in the position shown in full lines. If desired, thumb nuts 34^f may secure the rods 30^e in their elevated positions. The sliding frame formed by the slides 24^e and the parts carried thereby is projected when the bed frame is upright. It is desir-

able in all of the different embodiments to provide the bars with securing devices for holding the bed clothes thereto.

With the end in view of inclosing the bed frame when the latter is upright, there may be provided on opposite sides of the bed frame two pairs of screen members, one member of each pair being arranged to cover an edge or side of the mattress, while the other member is arranged to cover partially the under side of the bed frame. Preferably, the covering of the bottom of the bed frame and the folding legs is effected by providing two hinged screen members 38, each mounted on hinges 39 and 40, the latter of said hinges being projected downwardly a greater distance from the side rails of the bed frame than the other, so that the axis of turning of the screen member 38 is at a slight angle to the plane of the bed frame, whereby when the bed frame is upright and slightly inclined, the screen members will be vertical. The space provided between the bed frame and the screen members may be utilized for storing the pillows or night garments. When the bed is in position of use, the screen members 38 depend from the sides of the bed frame. To the edges of the screen members 38 the screen members 41 are connected by three-leaf hinges 42. These hinges permit the screen members to swing in order to cover the opposite edges of the mattress and bed clothes, as shown in Figs. 1 and 2, and, in addition, to hang in a pendent condition at the sides 45 of the bed frame when the latter is in position for use, as shown in Figs. 3 and 4. The lower free corners of the screens 38 and 41 are cut away at 43 in order that the screens will not interfere with the swinging of the bed frame on its pivot to and from an upright position, the screens during such swinging lying in parallel relation, as 50 shown in Fig. 3.

From the foregoing it will be seen that the bed clothes are automatically separated from the mattress and each other when the bed frame is swung upwardly, and upon the lowering of the bed frame the bed clothes fall into position on the mattress. Each element of the bed clothes is preferably held by a separate rod and the rods move relatively to each other. The bed clothes securing means is separate from the foot legs so that the bed clothes may be adjusted when the bed is in position for use. The bed clothes securing means is mounted on a frame which is movable longitudinally of the bed frame in order that the bed clothes may be elevated above the floor when the bed frame is upright. The bed frame may be inclosed by screening means attached to the bed frame so as not to interfere with the use of the bed, and the mattress is suspended from the swinging end of the bed frame so that its 55 60 65 70 75 80 85 90 95 100 105 110 115 120 125 130

sides are free in order that the bed clothes may be tucked under the mattress.

What I claim as my invention and desire to secure by Letters Patent is:—

5. 1. In a bed, a support, a bed frame mounted to swing thereon, and a frame arranged at the swinging end of the bed frame and movable longitudinally of the bed frame, said longitudinally-movable frame carrying 10 means for holding the different bed clothes in spaced relation when the bed frame is thrown to an upright position.
2. In a bed, a support, a bed frame mounted to swing on the support, means for securing the bed clothes in a spaced relation 15 at the swinging end of the frame, said means embodying guides at opposite sides of the bed and rods movable on said guides, and spacers carried by the rods.
- 20 3. In a bed, a support, a bed frame mounted to swing on the support, and means for securing the bed clothes at the swinging end of the frame, said means embodying guides at opposite sides of the bed and means movable on said guides and having the bed clothes secured thereto, the guides inclining with reference to the plane of the bed frame so that when the latter is swung to an upright position the bed clothes securing means 25 will move automatically on the guides to space the bed clothes from a mattress on the bed frame.
4. In a bed, a support, a bed frame mounted to swing thereon, supporting means for 30 the free or swinging end of the bed frame, and means movably supported on the bed frame at the swinging end for securing the bed clothes in spaced relation when the bed frame is thrown to an upright position, said 35 securing means being movable relatively to

the supporting means to a position under the swinging end of the bed frame for the purpose of tucking under the bed clothes after the bed frame has been lowered.

45 5. In a bed, a support, a bed frame mounted to swing on the support, a plurality of rods for holding the bed clothes at the swinging end of the frame, and guides for supporting said rods, said guides being extended under the bed frame to permit the 50 rods to pass under the said frame in order to carry the bed clothes under the frame at the foot of the bed.

55 6. In a bed, a support, a bed frame mounted to swing on the support, and means for securing the bed clothes in spaced relation at the swinging end of the bed frame comprising a pair of guides and a plurality of rods each formed of a single piece of wire bent at its ends to provide two loops through 60 which the guides extend, the free ends of the wires being formed with hooks detachably engaging the wire so as to permit the rods to be readily disconnected from their 65 guides.

70 7. In a bed, a support, a bed frame mounted to swing thereon, and a bed clothes supporting frame arranged at the swinging end of the bed frame and movable longitudinally of the bed frame.

75 8. In a bed, a support, a bed frame mounted to swing thereon, and means for securing the bed clothes at the swinging end of said bed frame, said means being movable longitudinally of the bed frame so that the bed clothes may be elevated out of contact with the floor when the bed frame is swung to an upright position.

GEORGE R. McALLASTER.
